UNITED STATES PATENT OFFICE.

SETH B. HENSHAW, OF CHARLESTON, WEST VIRGINIA, ASSIGNOR TO CHARLESTON
WINDOW GLASS CO., OF CHARLESTON, WEST VIRGINIA, A CORPORATION OF
WEST VIRGINIA.

CAPPING-HORSE FOR HOLLOW GLASS CYLINDERS.

1,263,668.

Specification of Letters Patent. Patented Apr. 23, 1918.

Application filed August 5, 1915. Serial No. 43,810.

To all whom it may concern:

Be it known that I, SETH B. HENSHAW, a citizen of the United States, and a resident of Charleston, in the county of Kanawha, and State of West Virginia, have invented certain new and useful Improvements in Capping-Horses for Hollow Glass Cylinders, of which the following is a specification.

10 My present invention relates generally to window glass machinery, and more particularly to what is commonly known as a capping horse for the support of a drawn hollow glass cylinder during the cutting 15 thereof into lengths.

Supports of this character now include a frame which is secured a short distance from the drawing furnace, to which frame are pivotally connected a series of transverse arms, having semi-circularly curved portions at one or both sides of the frame. In either case these curved portions receive sectional wooden sleeves directly engaging the hollow glass cylinders which the curved 25 portions of the arms are adapted to receive for the purpose of capping, and springs, in the nature of compression springs, extend between the said supporting arms and the said frame at that side of the frame next 30 to the curved cylinder receiving portions of the arms, being necessarily connected with the latter in a manner preventing ready detachment, and necessitating normal outstanding positions of the supporting arms at all times.

It is therefore the object of my invention to provide a horse, the supporting arms of which have curved cylinder receiving portions at one side of the frame, and extensions 40 projecting beyond the opposite side of the frame, the springs in this instance in the nature of retractile springs, being detachably connected at their outer ends to these latter extensions of the arms so that 45 when detached, the arms may swing on their pivots to vertical position and thus reduce to a minimum the floor space taken up by the capping horse when not in use.

50 My improvements will be better understood from the following detailed description thereof, reference being made to the

accompanying drawing, forming a part of this specification, and in which—

Figure 1 is a side elevation of a capping horse constructed in accordance with my 55 invention.

Fig. 2 is an enlarged vertical transverse section taken therethrough substantially on line 2—2 of Fig. 1, illustrating the supporting arms in their normal horizontal out-standing position, and

Fig. 3 is a similar view illustrating the springs detached and the arms dropped in disuse.

Referring now to these figures, the frame 65 of my improved horse, includes as usual the upper and lower parallel longitudinal bars A and A' respectively, extending through and connected by a plurality of uprights B, the lower ends of the latter of which are 70 secured by bolts or other suitable means as indicated at C in Figs. 2 and 3, to the floor of the factory in which the horse is utilized, at a short distance from the drawing furnace in connection with which the horse 75 is erected.

The supporting arms D, of which there are a series as particularly shown in Fig. 1, are intermediately and pivotally connected to the upper bar A of the frame, by 80 intermediately bending these arms around the bars to loosely engage the same as best seen by reference to Figs. 2 and 3, the semi-circularly curved cylinder receiving portions D' of these arms extending to one side 85 of the frame and receiving as usual the sectional wooden sleeve E on which the cylinders supported directly engage.

In accordance with my invention, these supporting arms D are provided with 90 straight horizontal extensions D² projecting at the relatively opposite side of the frame as clearly seen in Fig. 2, these extensions D² having curved hooks d at their extremities engaged by the upper outer ends of retractile 95 springs F, the lower ends of which springs are connected as usual to the lower bars A' of the frame.

In this manner it will be seen that the springs extend to the relatively opposite 100 side of the frame as compared to their usual extension at the present time for connection

with the supporting arms D immediately adjacent their semi-circularly curved portions D'.

Furthermore, by utilizing the springs in the particular manner shown and described, I am enabled to employ retractile springs and secure better, truer, and more uniform movements of the supporting arms under the tension of the springs than can be obtained by the use of compression springs at present.

In addition to the above, however, it is to be particularly noted that I am enabled by the arrangement above described to detachably connect the springs F to the supporting arms, thus enabling the arms to drop to the position either shown in full lines of Fig. 3, of their own accord and weight, or preferably to the position shown in dotted lines in Fig. 3 by swinging the curved portions D' over the top of the frame, the space between the upper and lower bars A and A' being somewhat greater than the length of the extensions D'. Thus when a horse is in disuse, its arms may be swung downwardly to substantially vertical positions, and out of the way of operators passing along both sides of the frame, thus reducing to a minimum the floor space taken up by the machine when not in use.

I claim:—

1. A capping horse for hollow glass cylinders including a supporting frame, a plurality of supporting arms pivotally connected to the frame and having cylinder-receiving portions at one side of the frame, and retractile springs extending from the frame and detachably engaging portions of the said arms at the opposite side of the frame, for the purpose described.

2. A capping horse for hollow glass cylinders including a supporting frame, a plurality of normally horizontal supporting arms pivotally connected to the frame and having curved cylinder receiving portions at one side of the frame, and retractile springs

extending from the frame at the relatively opposite side thereof from the cylinder receiving portions of the said arm, said springs being detachably connected to portions of the supporting arms, for the purpose described.

3. A capping horse for hollow glass cylinders including a supporting frame, a plurality of normally horizontal supporting arms pivotally connected to the frame and having cylinder receiving portions at one side of the frame, and extensions projecting at the opposite side of the frame, and springs extending between the frame and the said arms and detachably connected to the said extensions of the latter, for the purpose described.

4. A capping horse for hollow glass cylinders including a supporting frame, a plurality of supporting arms pivotally connected to the frame and having cylinder receiving portions at one side of the frame, and extensions projecting at the opposite side of the frame and provided with hooks at their extremities, and retractile springs extending between the frame and the said arms and detachably engaging the said hooks at the extremities of the arm extensions, for the purpose described.

5. A capping horse for hollow glass cylinders comprising a supporting frame including an upper horizontal bar, a plurality of normally horizontal supporting arms each consisting of a rod intermediately bent around said horizontal frame bar whereby to form a fulcrum on which the arm may swing vertically, each arm having a curved cylinder receiving portion at one side of the frame and an extension projecting at the opposite side of the frame, and a retractile spring extending from the frame and normally engaging said extension.

SETH B. HENSHAW.
